UNITED STATES PATENT OFFICE.

CHARLES A. McCUNE, OF JERSEY CITY, NEW JERSEY, ASSIGNOR TO THE COMMERCIAL ACETYLENE COMPANY, OF NEW YORK, N. Y., A CORPORATION OF NEW JERSEY.

LAMP.

956,720.

Specification of Letters Patent.

Patented May 3, 1910.

Application filed January 22, 1910. Serial No. 539,518.

To all whom it may concern:

Be it known that I, CHARLES A. McCUNE, a citizen of the United States, residing at Jersey City, county of Hudson, State of New Jersey, have invented certain new and useful Improvements in Lamps, of which the following is a full, clear, and exact description.

10 My invention relates to improvements in lamps, particularly useful for car lighting.

The object of my invention is to provide an improved inverted mantle lamp so constructed as to guard against breakage of mantles when lighting, and also so constructed as to prevent particles of broken mantles from falling on persons who may be under the said lamp. These and other objects will be apparent from an examination of the accompanying drawings and a reading of the following description.

In the accompanying drawings, Figure 1 is a central vertical sectional view of my improved lamp. Fig. 2 is a detail view also in section.

25 The lamp described is designed to be supported from overhead and comprises suitable supporting arms 1—1^a. In the particular instance, the supporting arm 1 constitutes a pipe for the gas supply. These arms 1—1^a make suitable connection with the frame 2 of the lamp, which has a central upward passage, in this particular instance furnished by a tube-like center draft-member 3, which projects well down below the frame 2.

35 4 is a globe suspended from the frame 2 and connected thereto in any desired manner, whereby it may be readily attached or detached in the event of breakage. The globe 4 has a central opening directly underneath the mantle hereinafter described, said opening being preferably bounded by a cone shaped upwardly directed wall 4^a.

40 5 is a screen carried by the globe 4 and covering the central opening, said screen being domed upwardly in its preferred form so as to lie closely adjacent to the mantle.

6 conventionally represents the mantle mounted on a suitable holder 7 carried by the tube 8, which in turn is connected by pipe 9 with the supply pipe 1. The mantle 6 is located between the lower edge of the central outlet 3 and the screen 5, being directly over and close to the latter.

In lighting the lamp by this improved construction, a lighted match may be applied 55 close to the mantle 6 and underneath the screen 5, the flame from the match passing through the screen (the mesh being coarse enough to permit the passage of said flame) and into contact with the gas around the 60 mantle 6, whereupon said gas is ignited.

By this construction the screen 5 not only protects the mantle from injury by the match or taper used for lighting, but it also protects any one who might be standing under the lamp from falling incandescent portions of the mantle 6, since said mantle, should it break, will fall upon the screen 5 and be jarred therefrom into the space around the cone 4^a and within the globe 4. 70 By this simple expedient not only does the screen operate as a guard, but it also affords proper ventilation from below.

What I claim is:

In a gas lamp of the character described, 75 a frame, an inverted burner of the incandescent mantle type carried thereby, a globe also carried thereby, the latter having a central opening directly under the mantle, and a protecting perforated screen covering said 80 opening and arranged close to said mantle— said perforated portion extending across said opening and directly under the mantle whereby said burner may be lighted through said screened opening.

CHARLES A. McCUNE.
